UNITED STATES PATENT OFFICE

155,477

DESIGN FOR A TOY FIGURE

Bertram M. Brown, Providence, R. I., assignor to Rosbro Plastics Corporation, a corporation of Rhode Island

Application January 30, 1948, Serial No. 144,142

Term of patent 14 years

(Cl. D34—4)

To all whom it may concern:

Be it known that I, Bertram M. Brown, a citizen of the United States, residing in Providence, in the county of Providence and State of Rhode Island, have invented a new, original, and ornamental Design for a Toy Figure, of which the following is a specification, reference being had to the accompanying drawing, constituting a part thereof.

Fig. 1 is a side elevation of a toy figure, showing my new design;

Fig. 2 is a front view; and

Fig. 3 is a top plan view thereof.

I claim:

The ornamental design for a toy figure, substantially as shown.

BERTRAM M. BROWN.
